Fig. 2.

UNITED STATES PATENT OFFICE.

EDWARD R. ALLEN, OF CORNING, NEW YORK.

POTATO-DIGGER.

1,133,908.

Specification of Letters Patent. Patented Mar. 30, 1915.

Application filed September 19, 1912. Serial No. 721,287.

To all whom it may concern:

Be it known that I, EDWARD R. ALLEN, a citizen of the United States, and resident of Corning, in the county of Steuben and State 5 of New York, have invented certain new and useful Improvements in Potato-Diggers, of which the following is a specification.

This invention relates to machines for digging potatoes and has for one of its objects the provision of a machine which is 10 efficient in operation and is capable of throwing the potatoes to either side of the furrow.

Another object is to provide a machine 15 which may be folded into a convenient position to be transported on its own wheels without operating the digging mechanism.

With these and other objects in view, as 20 will appear from the following description, the invention may be embodied in various forms of construction one of which is illustrated in the accompanying drawings, in which:

Figure 1 is a side elevation of the machine 25 with certain parts removed and other parts shown in section; Fig. 2 is a plan view of the machine; and Fig. 3 is a fragmentary section on the line 3—3 of Fig. 2.

Referring to the drawings, 10 indicates a 30 shaft on which are mounted the wheels 11 and 12, these wheels being secured to the shaft in any suitable manner. A yoke 13, having bearings 14 and 15 for the shaft 10, extends forwardly of the shaft and has secured thereto the pole 16, this pole serving as a means by which the machine may be 35 drawn and guided by horses. The shaft 10 has mounted thereon the oppositely arranged bevel gears 17 and 18, these gears 40 being arranged between the bearings 14 and 15. A member 19 is slidably arranged on the shaft 10 between the gears 17 and 18 and has secured thereto one end of a shaft 20, the other end of this shaft being secured in 45 the head or block 21. The member 19 has a flat upper surface 22 in which is a groove 23 adapted to receive a tongue 24 on a member 25 which is arranged between the gears 17 and 18 and preferably held thereby against 50 movement longitudinally of the shaft 10. The member 25 carries a forwardly extending bracket 26 to which is secured a suitable guard 27 which is adapted to prevent dirt and other materials from getting into the 55 gear teeth from above the machine. The

member 19 is provided with a pair of upwardly projecting lugs 28 to which is secured the plate or quadrant 29 by means of the bolts 30 and 31. Rearwardly of the lugs 28 is a lug 32 which forms a rest for the 60 plate 29 and helps support the latter. The plate 29 is notched at its rearward end to provide fine teeth as indicated at 33, and a lever 34 is pivoted to the plate 29, by means of a bolt 35, and carries on its under side a 65 latch 36 which engages the notches in the plate 29 and holds the lever. The lever 34 is also pivoted to the member 25 by means of a bolt 34^a which passes through an elongated slot 34^b in the lever. A spring 37 is 70 arranged between the latch 36 and the abutment 38 carried by the lever 34 and holds the latch in the notch in the quadrant, and a rod 39 is connected with the latch 36 and with an operating lever 40 adjacent the end 75 of the lever 34. This construction permits the latch 36 to be withdrawn from the notches in the quadrant when the operator grasps the end of the lever 34.

An upright bracket 41 may be pivoted or 80 otherwise secured to the member 21 and is provided with the lateral extensions 42 having the slot 43 through which passes the lever 34. The upper end of the member 41 has pivoted thereto a rod 44 provided with 85 suitable notches 45 and extending forwardly from the bracket and through a suitable opening in the upright bracket 46 carried by the pole 16. The member 21 also has secured thereto the handles 47 by means of 90 which the machine may be guided.

The shaft 20 has arranged thereon a sleeve 48 which carries the bevel pinion 49, this pinion being adapted to coöperate with the gears 17 and 18 to form a driving connection between the shaft 10 and the sleeve. At 95 its rearward end the sleeve 48 is connected with the hub 50 of the bevel gear 51 by means of a suitable jaw clutch 52. From the lower side of the member 21 extends a shaft 53 having secured on its lower end the lifting plow or digger 54. Arranged above the digger 54 is a hub 55 having projecting therefrom the arms 56. A bevel gear 57 is loosely arranged on the shaft 53 above the hub 55 and meshes with the gear 51 and is provided with the downwardly projecting rods or clutch members 58 which engage the hub 55 and cause the hub to rotate with the gear. 100 105 110

When in operation the machine will ordinarily be drawn by horses and the shaft 10 will be caused to rotate. When the pinion 49 stands in the position shown in Fig. 2 where it is midway between the gears 17 and 18 these gears will rotate freely. If however the lever 34 is shifted either to the right or left of the position shown in Fig. 2 the pinion 49 will be moved into engagement with one of the gears 17 or 18 and thus drive the hub 55.

The plow or digger 54 will disintegrate the soil that surrounds the potatoes and as the plow advances the soil and the potatoes will be carried upwardly thereon and delivered into the arms 56 carried by the hub 55. The loose soil will pass through the spaces between the arms, and the potatoes will be thrown by centrifugal force to the side of the furrow. It will be readily understood that by having the pinion 49 in mesh with the gear 17 the potatoes will be thrown to one side of the furrow and by having the pinion in mesh with the gear 18 the direction of rotation of the hub 55 will be reversed and the potatoes thrown to the other side of the furrow. It will also be understood that when the pinion 49 is in neutral position the hub 55 will not be rotated. The machine may be conveniently folded for purposes of transportation by lifting the handles 47 so that the digger 54 is raised to any desired height above the ground. When so elevated the parts will be held by the engagement of the notches 45 with the bracket 46. Wear of the teeth of the pinion 49, or the gears 17 and 18 may be compensated for by moving the pinion farther to the right or left so as to bring the teeth into engagement, the teeth of the quadrant being made fine to permit adjustment of the pinion for this purpose.

Having thus described the invention what is claimed is:

1. In a machine of the class described, the combination of a shaft, a pair of wheels mounted on said shaft, a pair of bevel gears secured to said shaft, a lifting plow, a throwing wheel adapted to receive the potatoes from said lifting plow and deliver the same at the side of the path of the machine, a member fixed between said gears, a second member slideable on said shaft, a pinion carried by said second member and arranged between said gears, means operatively connecting said pinion with said throwing wheel, a lever pivotally connected with said members, a quadrant carried by one of the said members, and a latching mechanism carried by said lever and cooperating with said quadrant to hold said lever in position.

2. In a machine of the class described, the combination of a shaft extending transversely of the machine, means for driving said shaft, a second shaft extending rearwardly of said first mentioned shaft, a third shaft rigidly connected with said second shaft and extending transversely thereof, a lifting plow carried by said third shaft, a throwing wheel rotatably mounted on said third shaft, a gear rotatably mounted on said second shaft and adapted to drive said throwing wheel, a second gear rotatably mounted on said second shaft, a clutch for connecting said gears, and means for reversibly driving said second gear from said first mentioned shaft.

In testimony whereof I affix my signature in presence of two witnesses.

EDWARD R. ALLEN.
